WITNESS:

UNITED STATES PATENT OFFICE.

JOSEPH B. MAY, OF BEDFORD, PENNSYLVANIA.

RUSTIC-CHAIR-MAKING DEVICE.

Application filed March 25, 1924, Serial No. 701,796.

To all whom it may concern:

Be it known that I, JOSEPH B. MAY, a citizen of the United States, residing at Bedford, in the county of Bedford and State of Pennsylvania, have invented new and useful Improvements in Rustic-Chair-Making Devices, of which the following is a specification.

It is the purpose of the present invention

10 to provide a chair form, by means of which rustic chairs of different design can be quickly and conveniently made, certain parts of the form being adjustable to also permit of the variation in size of the chair
15 made thereon.

More specifically stated, the invention includes an adjustable back piece which is mounted on a base utilized to support the legs of the chair, the back piece being capable of movement toward and away from a fixed part of the seat support, whereby chairs of different size and design, can be made, and also the inclination of the back with relation to the seat varied.

25 The nature and advantages of the invention will be better understood when the following detailed description is read in connection with the accompanying drawings, the invention residing in the construction, 30 combination and arrangement of parts as claimed.

In the drawings forming part of this application, like numerals of reference indicate similar parts in the several views, 35 and wherein:

Figure 1 is a side elevation of the form showing certain parts of the chair associated therewith.

Figure 2 is a front elevation.

40 Figure 3 is a top plan view.

Figure 4 is a sectional view taken on the line 4—4 of Figure 3.

The form constituting the subject matter of the present invention includes a base 45 10 of elongated contour in plan and supported by uprights 11 adjacent the corners thereof. Reposing upon this base and arranged transversely thereof are spaced parallel strips 12 and 13 respectively, both of 50 which projects beyond the opposed longitudinal edges of the platform, and each of which is formed with openings 14 adjacent the ends thereof. Also mounted upon this platform is the stationary part of the seat support, which part includes spaced up-

rights 15 connected by a transverse member 16 from which rises pins 17 for a purpose to be hereinafter described. This seat support is arranged directly behind the transverse strip 12, and is braced by diagonally disposed members 17' which are arranged between the strips 12 and 13 respectively and terminally secured to the uprights 15 and the base 10.

The back piece of the form consists of a pair of spaced members 18 which slightly converge toward their upper end, and these members are hingedly mounted upon the transverse strip 13 above referred to. These members are connected together adjacent

70 their upper ends by a plurality of transverse strips 19 which are closely associated as clearly shown in Figure 2, and each of these latter mentioned strips is provided with an opening to receive an adjustable bolt 20 clearly illustrated in Figure 4. Some of these bolts have their forward ends passed through clamping bars 21 and then offset as at 22 against one side of the bars to hold the parts associated, and these 80 clamping bars are movable toward and away from the spaced members 18 by adjusting the bolts 20 through the openings in the cross strips 19. This is accomplished by rotating the nuts 23, one of which is 85 threadedly associated with each bolt as shown in Figure 4. One of the bolts 20 terminates at its forward end to provide an eye 24, and this eye receives a substantially U-shaped clamping bar 25 as shown in Figure 2. In addition to these clamps, the 90 spacing members 18 of the form for the back of the chair is provided with transverse openings to receive similar bolts 26, each of which has associated therewith a 95 nut 27 to effect an adjustment of these bolts, the latter terminating at their forward ends to provide hook like extremities 28 for a purpose to be hereinafter set forth. The component parts of the back of the chair 100 are adapted to be clamped to this back piece, and subsequently secured to the seat of the chair indicated at 29. The seat 29 is not only supported upon the cross piece 16 above referred to, but is also supported by 105 a cross piece 30 which is arranged transversely of and secured to the spaced members 18, and by reason of the fact that these members are mounted for hinged movement with relation to the base 10, it 110

is manifest, that the cross piece 30 can be moved toward and away from the cross piece 16 to accommodate seats of different dimensions, and at the same time provide for the desired inclination of the back with relation to the seat. The back piece of the form is held fixed relative to the base 10 subsequent to its adjustment, by means of the diagonally disposed supports 31 which are 10 pivoted to the spaced members 18 of the back piece, and arranged to slide through divided loops 32 which are formed by the terminal of strips 33 secured at one end of the base 10 as shown in Figure 3. The 15 lower ends of the supports 31 are provided with spaced openings 34 any of which may be brought into alignment with the said loops incident to the adjustment of the back piece, to accommodate a pintle or pin 35 which of course holds the back piece fixed 20 in its adjusted position. For the purpose of holding the seat 29 on the cross piece 30 I make use of a loop 36, the ends of which are twisted in a manner to permit this 25 loop to associate with these parts or removed therefrom as the occasion may require.

In practice, the front legs of the chair indicated at 37 and the back legs of the 30 chair indicated at 38 are adapted to be arranged between the runners 39' and nailed or otherwise secured thereto, with these legs projecting a slight distance beneath the runners to be received by the openings 14 in the 35 transverse strips 12 and 13 respectively which are mounted upon the platform 10. Thus the runners and the various legs are supported on the form, and from an inspection of Figure 2 it will be noted that the 40 rear legs 38 are of a length to form part of the back of the chair, and slightly converge toward their upper ends. The clamping bars 21 clamp these legs between the said bars and the spaced members 18 forming part of 45 the back piece of the form, while the U-shaped clamping element 25 straddles the legs 38 in a manner to hold them in proper spaced relation. The main or body portion of the back of the chair herein indicated 50 at 39 is then arranged upon the upper extremities of the legs 38 and nailed or otherwise secured thereto, while the side portions of the back piece 39 are received by the hook like extremities 28 of the bolts 26 carried 55 by the members 18. These bolts 26 of course hold the side portions of the main back piece of the chair in proper position, while the terminals of the side portions are being secured to the seat 29 in any suitable manner. 60 It will be understood that the component parts of the back of the chair are first secured together in the manner described, after which the seat 29 is arranged upon the cross piece 16 of the fixed part of its support, and the back piece of the form subsequently

swung upon its hinges 40 in order to obtain the proper inclination of the back with relation to the seat and incidently position the cross piece 30 in proper relation to the adjacent edge of the seat 29, which of course depends upon the size of the seat and the desired inclination of the back therefor. The seat is formed with an opening to receive the loop 36 which of course holds the seat associated with the cross piece 30, while the side portions of the main part 39 of the back is being nailed or otherwise secured to said seat. If the chair is to be provided with arm rests, the front legs 37 will be made of a size to extend an appreciable distance 70 above the seat 29, and arm rests, not shown, will then be nailed upon the upper ends of these front legs and the side members of the main back piece 39 of the chair. By reason 75 of this invention, rustic chairs can be quickly and conveniently constructed and the design of the chair can be varied by adjusting the back piece as above described, and also by adding additional slats or back supports 80 after the chair has been removed from the form.

While it is believed that from the foregoing description, the nature and advantages of the invention will be readily apparent, I 85 desire to have it understood that I do not limit myself to what is herein shown and described, and that such changes may be resorted to when desired as fall within the scope of what is claimed.

Having thus described the invention, I 100 claim:

1. A chair form of the character described comprising a base, a seat support mounted thereon, a back support arranged upon the base means for supporting said back for pivotal movement toward and away from the seat support, a cooperating seat supporting element carried by the back support, and clamping devices mounted on the back support for clamping the component parts of the back thereto for the purpose specified.

2. A chair form of the character described comprising a base, a stationary seat support rising therefrom, a back support mounted upon the base for pivotal movement toward and away from the stationary seat support, a movable seat supporting element carried by the back support, means connecting the back support with the base and utilized to hold the back support fixed relative to the base in any adjustable position, and clamping devices carried by the back support and holding the component parts of the back of the chair associated therewith.

3. A chair form of the character described comprising a base, spaced transverse strips arranged upon the base and projecting beyond the opposed longitudinal edges thereof, said strips having openings adjacent the ends thereof, and adapted to receive the legs of

the chair to be made on said form, a stationary seat support rising from the base immediately adjacent one of said strips, a back support hingedly mounted on the other strip and susceptible of movement toward and away from the stationary seat support, a moveable seat supporting element carried by the back support and arranged to cooperate

with the stationary seat support, means for holding the back support fixed relative to the base in any desired position, and clamping devices carried by the back support for holding the component parts of the back of the chair associated therewith.

In testimony whereof I affix my signature. 15
JOSEPH B. MAY.
